MEDICINE DROPPER

Joseph M. Mitchell, % Baronar Products Co.,
High St., Clinton, Mass.

Filed Sept. 19, 1962, Ser. No. 71,763

Term of patent 14 years

(Cl. D83—1)

FIG.4

FIG.1

FIG. 1 is a view in front elevation of a medicine dropper showing my new design; the undisclosed rear is substantially the same in appearance as the front except for the omission of the facial features.

FIG. 2 is a view in side elevation thereof;

FIG. 3 is a top plan view thereof, and

FIG. 4 is a section on line 4—4 of FIG. 1.

I claim:

The ornamental design for a medicine dropper, as shown and described.
